CLAIM

I claim the ornamental design for an anchor, as shown and described.

DESCRIPTION

FIG. 1 is a front perspective view of the anchor embodying my design;

FIG. 2 is an enlarged front elevational view of the anchor shown in FIG. 1;

FIG. 3 is an enlarged rear elevational view of the anchor shown in FIG. 1;

FIG. 4 is a top plan view of the anchor shown in FIG. 1;

FIG. 5 is a bottom view of the anchor shown in FIG. 1;

FIG. 6 is an enlarged right side elevational view of the anchor shown in FIG. 1; and,

FIG. 7 is an enlarged left side elevational view of the anchor shown in FIG. 1.
